UNITED STATES PATENT OFFICE.

BERNARD A. BEIREN, OF NORWOOD, OHIO, ASSIGNOR TO ALLIS-CHALMERS COMPANY, A CORPORATION OF NEW JERSEY, AND THE BULLOCK ELECTRIC MANUFACTURING COMPANY, A CORPORATION OF OHIO.

CORE-SPACING MEMBER FOR DYNAMO-ELECTRIC MACHINES.

No. 925,271.

Specification of Letters Patent.

Patented June 15, 1909.

Application filed August 31, 1906. Serial No. 332,773.

To all whom it may concern:

Be it known that I, BERNARD A. BEIREN, citizen of the United States, residing at Norwood, in the county of Hamilton and State of Ohio, have invented certain new and useful Improvements in Core-Spacing Members for Dynamo-Electric Machines, of which the following is a full, clear, and exact specification.

10 This invention relates to improvements in dynamo-electric machines and particularly to spacing and ventilating members for laminated cores of such machines.

15 The object of the invention is the provision of core spacing members which can be easily and cheaply manufactured, which are strong mechanically and which will permit an ample ventilation or circulation of air regardless of the size of the core.

20 In carrying out my invention, I employ for each spacing member, instead of a single plate or casting, having all the spacing ribs or projections, two oppositely disposed plates, each carrying part of the spacing projections, the projections of one plate bearing 25 on the other plate intermediate the projections of that plate. With this arrangement and construction, the angular spacing or distance between the adjacent projections 30 carried by each plate is twice as great as in the ordinary constructions wherein single plates are employed.

My invention may be further briefly summarized as consisting in certain novel details 35 of construction, and combinations and arrangements of parts which will be described in the specification and set forth in the appended claims.

40 For a better understanding of my invention, reference is had to the accompanying drawings in which—

Figure 1 is a partial longitudinal section of an armature core having spacing and ventilating members constructed and arranged 45 in accordance with one form of my invention. Fig. 2 is a front elevation of one of the core spacing plates employed in the construction shown in Fig. 1. Fig. 3 is a plan view of a portion of the core showing the 50 arrangement of the two co-operating plates of one spacing member and showing the staggered relation of the spacing ribs. Fig. 4 is a front elevation of a modified form of

core spacing plate. Fig. 5 is a plan view of a portion of a core showing a spacing 55 member formed by plates having the construction shown in Fig. 4. Fig. 6 is a portion of a section of the core showing the two plates of the type shown in Fig. 4 and showing the staggered or interlocking relation of 60 the spacing projections.

Referring now to the figures of the drawing, 10 represents the shaft of the rotary member of a dynamo-electric machine, said shaft having mounted thereon a spider 11 65 and a core 12 built up of laminæ which may be secured to the spider in any desired manner, preferably by dove-tail connections, and which are clamped between end heads or members 13 at the ends of the spider. The 70 laminæ are arranged in groups which are spaced apart by my improved spacing members so as to form ventilating spaces at intervals in the body of the core, which spaces communicate with transverse ventilating 75 spaces or passageways 14.

The spacing members constructed and arranged in accordance with my invention, each comprise a pair of oppositely disposed plates which in Figs. 1, 2, and 3 are designated 19, said plates having plain or smooth faces which abut against the end-laminæ of the adjacent groups and on the adjacent faces having spacing and ventilating projections, which, in the form of my invention 85 shown in Figs. 1, 2, and 3, consist of radial ribs 20. In the present case, by way of example, I have shown plates segmental in shape but it will be apparent that whether the plates are of the integral or segmental 90 type is immaterial to my invention. Each plate is provided with peripheral teeth 19^a which are equal in number to the number of core teeth and register with the latter and the ribs 20 of each plate are located in line 95 with alternate teeth and have, therefore, twice the angular spacing that they would have if arranged in line with all the teeth as in the usual constructions. When the laminæ and plates 19 are assembled, the plates 100 are so arranged that the ribs 20 of each plate bear on the opposite plate intermediate the ribs of that plate, with the result that the ribs are staggered or project alternately from opposite plates. The length of the 105 spacing ribs may, of course, be varied, but

in the present case they extend from the inner edge of the plate nearly to the bases of the peripheral teeth and while they do not brace the core teeth, this construction is preferred in some cases particularly in small cores for the reason that a better circulation of air can take place between the conductors (not shown) in the core slots, than would result if the ribs extended outward along the core teeth. It will be understood that when the ribs have substantially the length here shown the plates 19 will be of such a thickness and material that the peripheral teeth 19^a will have sufficient rigidity to support and brace the core teeth.

In the modification shown in Figs. 4, 5, and 6, each plate 21 is provided with spacing lugs or projections 22 which bear upon the opposite plate. In this case in line with each alternate tooth is a row of three projections which are spaced apart in a radial direction and in line with each of the remaining teeth there are two projections staggered relatively to the projections of the adjacent rows. The opposite plate of each bar is provided with an equal number of projections 22^a, but the order or arrangement is reversed so that when the plates are assembled, projections of each plate bear upon the opposite plate in the spaces between the projections of the latter plate, as is shown clearly in Fig. 6. Of course, it is to be understood that the number of projections and their order or arrangement may be varied from the number and arrangement shown in these figures. It will be seen that in this construction the teeth as well as the body of the laminae are braced, the construction being therefore a trifle stronger mechanically, but permitting a slightly less extensive circulation of air than in the construction first described.

While I have shown in Figs. 2 and 4 core spacing plates segmental in shape, it will be understood that between adjacent groups of laminae, a sufficient number of these segments will be arranged end to end so as to

extend entirely around the shaft or otherwise conform to the shape of the core.

I do not desire to be confined to the exact details shown but aim in my claims to cover all modifications which do not involve a departure from the spirit and scope of my invention.

What I claim as new and desire to secure by Letters Patent is:—

1. In a dynamo-electric machine, a laminated core, spacing members between the laminae dividing the latter into sections, each spacing member comprising a pair of toothed plates abutting against the end laminae of adjacent core sections, each of said pair of plates having projections which bear on the other plate, and are staggered so that the projections of one plate bear on the other intermediate the projections of that plate.

2. In a dynamo-electric machine, a laminated core, spacing members between the laminae dividing the core into sections, each of said spacing members comprising oppositely disposed plates each having on one side a plane surface bearing against the end laminae of a section and on the other side radial ribs which bear on the plate of the next adjacent section, the ribs of one plate bearing against the adjacent plate intermediate the ribs of that plate.

3. In a dynamo-electric machine, a laminated core, spacing members between the laminae dividing the latter into groups or sections, each spacing member comprising a pair of oppositely disposed toothed plates of greater thickness than the laminae each plate having ribs which project axially of the core and bear on the opposite plate, said ribs being staggered so that the ribs of one plate occur between the ribs of the other plate.

In testimony whereof I affix my signature, in the presence of two witnesses.

BERNARD A. BEHREND.
